UNITED STATES PATENT OFFICE.

JAMES T. COWLEY, OF BOSTON, MASSACHUSETTS, ASSIGNOR TO LAMSON CONSOLIDATED STORE SERVICE COMPANY, OF NEWARK, NEW JERSEY, A CORPORATION OF NEW JERSEY.

CONVEYING APPARATUS.

No. 866,264.

Specification of Letters Patent.

Patented Sept. 17, 1907.

Application filed May 18, 1905. Serial No. 260,927.

To all whom it may concern:

Be it known that I, JAMES T. COWLEY, of Boston, in the county of Suffolk and State of Massachusetts, have invented certain new and useful Improvements in Conveying Apparatus, of which the following is a specification.

My invention relates to that class of cable track conveyors so combined, constructed and operated as to utilize a car or carrier traveling thereon to automatically pick up and convey letters, packages or loose matter from a series of despatching stations or shelves located along the system and automatically discharge the said articles into any of a series of receiving stations located along the said system. These objects are accomplished by providing despatch stations or shelves so located that on passing beneath said shelves, a sweep mounted on the car or carrier will sweep any articles from the said shelves into the said carrier. At the receiving stations there are provided trip cams adapted to engage spring actuated clutches at each end of the carrier, releasing the said clutches and causing the bottom of the carrier to divide and swing outward discharging the articles. Cams are adapted to engage the bottom of the carrier immediately after discharging, said cams causing the bottom to assume its initial position whereupon the spring-actuated clutches lock the same into position. Numerous other important features are hereinafter described and particularly pointed out in the claims.

In the accompanying drawings which illustrate a construction embodying my invention, Figure 1 is a side view in elevation of the track and receiving station. Fig. 2 is a side elevation of track and despatching station. Fig. 3 is an enlarged side elevation of carrier and track. Fig. 4 is an end elevation of Fig. 3 looking in the direction indicated by the arrow. Fig. 5 is a plan view of the carrier showing the releasing device.

Like letters of reference refer to like parts throughout the several views:

The vertical standards A' are fixed to the table A and carry the adjustable cross pieces A² (Fig. 4) which are held in position by the bolts Q. The supporting track A³ is mounted on extensions of the said cross pieces A². Mounted in the yoke of said cross piece A² are the guide rails A⁴ A⁵. The grooved wheels B' are journaled in the frame B² and are adapted to travel on the track A³. The carrier B is suspended from the frame B² by the brackets B³; a rubber strip B⁴ is set in a slot in the plate B⁵ which plate is drop-fastened to the frame B² by the rod B⁶. The shelves or despatching stations D are mounted on the brackets D' which are adjustable on the vertical standards A' and held by the bolts Q. These shelves D are adjusted to allow the strips B⁴ to sweep over them.

The spring grip B⁷ is fixed to the frame B² by the set screws B⁸ and said spring grip engages the cable C. The guide rolls C' C² are journaled in the said frame B² and operate between the guide rails A⁴ A⁵. The horizontal cam strip B⁹ screwed to the frame B² acts upon the roll E forcing the cable supporting finger E² to one side allowing the passage of the carrier B, whence the said finger E² resumes its initial position by means of the spring E³ acting thereon. The endless cable C is supported by the pulleys C³ C⁴ forming a loop which may be mounted upon and driven by any suitable pulley or drum. The carrier B has the counterbalance weight F mounted on its side and on either end carries the face plates F' F². Pivoted to said face plates F' F² are the locking levers F³ and F⁴ respectively. The bottom of the carrier is divided into two swinging portions G, G', which are hinged to the sides of said carrier and adapted to swing outwardly. The portion G' in the closed position overlaps and holds the swinging portion G in position, extensions of said portion G' engaging the said locking levers F³ F⁴. The springs F⁵ F⁶ hold the said levers in position. Rolls H² H³ are pivoted to each of the swinging portions G and G' and are adapted to engage the cams H and H' which are mounted adjustably on the supports A' and held thereon by the bolts Q. A trip cam H⁴ (Fig. 5) is mounted on the standards A' and so angularly adjusted as to engage the fingers F⁷ F⁸ of the locking levers F³ F⁴ and releases the swinging portions of the carrier.

The operator stands at the case (Fig. 2) and places the desired articles upon either of the despatching stations D and the carrier actuated by the cable C traveling upon the track A³ upon passing the said shelves or despatching stations D sweeps the articles placed thereon into the carrier B by means of the sweep B⁴. The carrier upon coming to a receiving station (Fig. 1) engages the trip cam H⁴ which releases the locking levers F³ F⁴ thereby causing the swinging portions G, G' of the carrier to swing outward releasing the load into the receptacle thereunder. Upon passing said receiving station the cams H and H' engage the rolls H² and H³ of the swinging portions G and G' thereby causing the same to swing inward, the portion G assuming its position in advance of the portion G' which closes thereon, the levers F³ and F⁴ locking the same by means of the springs F⁵ and F⁶ acting thereon. On approaching the cable supporting finger E² the cam strip B⁹ on the carrier B engages the roll E forcing the said finger E² to one side allowing the carrier to pass. The spring E³ immediately causes the said finger E² to resume its initial position. Upon passing the pulleys C³ and C⁴ a depression in the track A³ dropping the carrier B below the cable C throws the grip B⁷ out of contact.

with said cable, the said grip immediately engages the cable C on passing the said pulleys.

Having thus described the nature of my invention and set forth a construction embodying the same, 5 what I claim as new and desire to secure by Letters Patent of the United States is:

1. In a conveying apparatus, a frame work, means supporting said frame work, tracks or guide rails mounted therein, a carrier adapted to travel on said tracks or guide rails, a propelling cable adapted to actuate said carrier, despatching stations or shelves located within the path of travel of said carrier, and means located on said carrier for sweeping articles on said despatching shelves or stations into said carrier.
  - 15 2. In a conveying apparatus, a frame work, means supporting said frame work, tracks or guide rails mounted therein, a carrier adapted to travel on said tracks or guide rails, a propelling cable adapted to actuate said carrier, despatching stations or shelves located within the path 20 of travel of said carrier, and yielding means located on said carrier for sweeping articles on said despatching stations or shelves into said carrier.
  - 25 3. In a conveying apparatus, a track or way, a carrier adapted to travel on said track or way, a propelling cable adapted to actuate said carrier, one or more despatching stations or shelves located in the path of travel of said carrier, and means located on the carrier for sweeping articles 30 from said despatching station or stations into said carrier.
  - 35 4. In a conveying apparatus, a track or way, a carrier adapted to travel on said track or way, a propelling cable adapted to actuate said carrier, one or more despatching stations or shelves located in the path of travel of said carrier, and yielding means located on the carrier for sweeping articles from said despatching station or stations into said carrier.
5. In a conveying apparatus, a track or way, a carrier adapted to travel on said track or way and provided with a releasable bottom, means for normally holding said bottom in its closed position, a propelling cable adapted to 40 actuate said carrier, one or more despatching stations or shelves located in the path of travel of said carrier, a receiving station located in the path of travel of said carrier, and means for releasing said bottom to allow the discharge of the contents of said carrier at said receiving 45 station.
  6. In a conveying apparatus, a track or way, a carrier adapted to travel on said track or way and provided with a releasable bottom, means for normally holding said bottom in its closed position, a propelling cable adapted to 50 actuate said carrier, one or more despatching stations or shelves located in the path of travel of said carrier, a receiving station located in the path of travel of said carrier, means for releasing said bottom to allow the discharge of the contents of said carrier at said receiving station, 55 actuating means adapted to close said releasable bottom after said discharge, and means for locking said releasable bottom in its closed position.
  7. In a conveying apparatus, a track or way, a carrier adapted to travel on said track or way, a propelling cable 60 adapted to actuate said carrier, one or more despatching stations located in the path of travel of said carrier, a receiving station located in the path of travel of said carrier, means located on the carrier for sweeping articles from said despatching station or stations into said carrier, 65 a receiving station located in the path of travel of said carrier, and means for discharging the contents of said carrier at said receiving station.

In testimony whereof, I have signed my name to this specification in the presence of two subscribing witnesses, 70 this 12th day of May 1905.

JAMES T. COWLEY.
